TRANSPARENCY MOUNT AND METHOD
OF MAKING SAME

Eugene G. Seary, Hastings on Hudson, N. Y.

Application October 9, 1948, Serial No. 53,735

5 Claims. (Cl. 40—158)

1

The general object of the present invention is to provide an improved transparency mount and method of making the same. My improved mount is well adapted for use in a projection printer or other projection apparatus in which light is projected through the transparency. My improved transparency mount is of the known type formed from a paper blank having two side-by-side apertures which may be brought into register by folding into parallelism the two sections, or flap portions of the blank at opposite sides of a fold line between the two apertures. The transparency included in such a mount, extends across the registering apertures and has a rim or marginal portion between portions of the sections adjacent and surrounding the apertures. Each section thus forms a frame surrounding the picture or image on the transparency which may be projected onto photographic material by a projection printer, or onto a screen by a projector of the type employed for screen exhibition purposes.

Ordinarily, it is practically essential that the rim portion of the transparency which extends between the sections of the mount should be substantially in register with, and bear against, a seat formed by a predetermined portion of one of the sections surrounding and adjacent the aperture in the latter. To facilitate the proper placing or seating of the transparency on the desired seat portion of one of the frame sections, various expedients have been devised for deforming the mount blank to provide projections at the margin of the seat which the edge of the transparency will engage when the latter is properly disposed relative to the seat portion of the mount blank. Each of the methods of thus outlining the transparency seat of paper mount heretofore employed, of which I have knowledge, has been open to the objection that its use results in the production of finished mounts which do not have smooth, flat external surfaces. Such surfaces are ordinarily desirable to facilitate the assembly of the mounts in stacks as is sometimes desirable, and insure when such mounts are inserted in projection apparatus, its transparency will lie in a predetermined plane. Furthermore, such deformation of the blank by the methods heretofore used have usually involved blank cutting operations which undesirably weaken the mount structure.

The primary object of the present invention is to provide a paper mount section with integral projections which outline the transparency seat portion of the section, and which are of such

2

character that the projections may be obliterated after the transparency is properly placed between the two mount sections or flaps, so that in the finished mount, the section will have suitably flat sides. In my novel method of making cardboard mounts, seat outlining projections are so formed by a blank indenting or embossing action that the projections may be subsequently eliminated by subjecting the mount to pressure. 10 In practice, the projections are ordinarily eliminated by the pressure applied to the mount to cause adhesive material between the adjacent sides of the two sections to form an adhesive bond between the portions of said sides in contact with one another. The adhesive material employed may vary widely in composition, and may be applied in any manner. In particular, the adhesive material composition and mode of application may be any of those heretofore successfully employed in the production of mounts of the general type described. Thus the adhesive agent used may be of the type used in what is commonly known as Scotch tape, comprising a layer of a tacky adhesive such as a rubber or vinyl compound which is applied to a mount surface to be bonded to another mount surface when the two surfaces are pressed together. Alternatively, one at least of the blank surfaces to be bonded together may be given a dry coating formed of an adhesive material, such as an animal glue which can be temporarily softened by wetting, or a temperature sensitive adhesive material, such as cyclized rubber, polyvinyl acetate or nitro cellulose, which softens when treated to a temperature appreciably above normal atmospheric temperatures.

30 In the form of the present invention which I now consider preferable, the adhesive material is of a pressure sensitive type adapted to form a good bond between the adjacent sides of the folded blank sections when suitably heated and subjected to a suitable pressure.

40 In one form of the invention, the bond connecting two sections of the blank and sealing the transparency between them, is formed in a single stage or operation, while in a second form of the invention, a bond is formed between portions of the sections in one operation before the transparency is inserted between the sections, and subsequently the transparency is inserted between the blank sections, and the latter are subjected to a second bonding operation which seals the transparency in place and completes the 50 bond between the sections.

The various features of novelty which characterize my invention are pointed out with particularity in the claims annexed to and forming a part of this specification. For a better understanding of the invention, however, its advantages, and specific objects attained with its use, reference should be had to the accompanying drawing and descriptive matter in which I have illustrated and described preferred embodiments of the invention.

Fig. 1 is a plan view of an unfolded apertured mount forming blank with a transparency engaging a seat portion at one side of one section of the blank;

Fig. 2 is a section through a portion of the blank on the line 2—2 of Fig. 1;

Fig. 3 is a section through the finished mount taken on the line 2—2 of Fig. 1;

Fig. 4 is an elevation of a mount forming press;

Fig. 5 is a plan view of one of the press platens; and

Fig. 6 is a plan view of a modified form of the platen shown in Fig. 5.

In Figs. 1, 2 and 3, I have illustrated the preferred form of my invention for use in the production of a mount in which a transparency is sealed in a mount and the sections of the mount are sealed together in a single operation. The mount forming paper blank C shown in Figs. 1, 2 and 3 comprises two substantially similar sections A and B formed with apertures a and b, respectively, which are brought into register when the blank is folded about a fold line D between the apertures a and b. As shown in Fig. 2, the score line D is defined by an incision extending into the lower portion of the blank C from the underside of the latter, as seen in Figs. 1 and 2. The blank sections A and B are shown as similar squares and the apertures a and b are shown as similar rectangles with rounded corners and having sides transverse to the fold line D which are longer than its sides parallel to the fold line, but the shapes of the sections A and B and apertures a and b may be modified as conditions make desirable. In ordinary practice, however, the sections A and B will be generally similar in shape and dimensions, and the apertures a and b will be shaped and proportioned relative to the transparency which is to extend across the registering apertures so that a predetermined marginal portion of the transparency E, may be held between the sections or flaps A and B, as shown in Fig. 3. As shown, the section B is provided with a seat F for the transparency E, which is outlined by projections G extending upward at the upper side of the section B as seen in Figs. 1 and 2. The seat F is shown as rectangular in outline and has each of its four sides in engagement with each of a plurality of projections G arranged in a row between the adjacent edge of the transparency and the adjacent outer edge of the section B.

In accordance with the present invention, the projections G are formed by an embossing or indenting action which produces an indentation g in the underside of the section B beneath each of the projections G at the upper side of the section. In practice, each projection G may well be of a height as seen in Fig. 2 which is appreciably greater than the thickness of the transparency E, so that the transparency may be manually moved rapidly into the position on the section B in which it is in accurate register with the seat F. In ordinary practice, the thickness of the blank C sufficiently exceeds that of the thin trans-

parency E so that projections F may be given adequate height by an embossing or indenting action without cutting or shearing the blank to an extent materially weakening the blank or interfering with its return to its desired flat form when subjected to suitable pressure. That pressure may be the pressure desirably employed in the final mount forming operation to establish a thin adhesive bond between the sides of the sections A and B in contact with one another.

As previously indicated, the shape and dimensions of the blank sections A and B and apertures a and b are not critical and may vary as the conditions of use make desirable. Merely by way of illustration and example and not by way of limitation, it is noted, however, that the drawings illustrate a mount designed for use in a projection printer in commercial use in reproducing color picture transparencies, each about $\frac{1}{8}$ of an inch wide and about $1\frac{1}{8}$ inches long. The sections A and B of the mount in which said transparencies are mounted are each slightly less than 2 inches square. While the apertures a and b may have identical dimensions, in the above mentioned design each aperture a is about three-hundredths of an inch longer and wider than the aperture b. The blanks C are formed of a relatively dense, hard cardboard about .020" thick. The thickness of the transparency E is ordinarily appreciably less than the blank thickness and in some cases is about .005". As will be apparent, the scale of each figure of the drawing is greater than one to one, and in Figs. 2 and 3, the vertical scale is greater than the horizontal scale.

In the form shown, each projection G may be formed by a punch which may be $\frac{1}{8}$ " in diameter, and has one end bevelled off so that the upper end of each projection is inclined at a small angle, for example, an angle of 30° to the plane of section B. As shown in Figs. 1 and 2, the inclined upper end surface of each projection G merges into the upper flat surface of the section B at the ends of an arc of less than 180° . Each uprising projection G is thus in the form of a portion of a cylinder transverse to the upper surface of the section B and having its convex side substantially tangent to the adjacent side edge of the seat F. With the projection G shaped and formed as described, the blank shearing effect, attending the formation of each projection may be confined to the separation of relatively small convex and concave blank portions adjacent the crown of the curved edge of the projection seen in Fig. 1. As shown, there are four projections G at each end of the seat F, and five projections G at each side of the seat F.

While as previously indicated, the adhesive material used to bond the sections A and B together when in contact, as shown in Fig. 3, may vary in composition and in the manner of its application, I preferably employ an adhesive material such as cyclized rubber, polyvinyl acetate or nitrocellulose, which is applied in a fluid or semi-fluid condition to the entire upper side of the blank as seen in Fig. 1, and which dries to form a solid coating which when at ordinary atmospheric temperatures, will not adhere to surfaces in contact therewith, but when heated to a softening temperature becomes sticky and will form a strong and durable adherent bond between the contacting surfaces of the sections A and B if the latter are pressed together while the adhesive is being softened and the latter is then cooled to normal atmospheric temperature. It is possible to form the

bond between the sections A and B when coated with adhesive material of the character specified, in various ways. For example, the sections may be pressed together by a flat iron hot enough to raise the adhesive temperature to about 300° F., and subjecting the mount to a transverse pressure of a couple of pounds or so per square inch.

In the commercial use of the invention, however, the bonding operation may advantageously be carried out in a suitable power press having at least one platen electrically heated. Such a press may be of the type diagrammatically illustrated in Figs. 4 and 5, which comprises a normally stationary lower platen I, and a superposed vertically movable platen J. As diagrammatically shown in Fig. 4, the platen J is carried by the lower end of a piston rod K' connected to a piston moving down and up in a fluid pressure cylinder K as air or other pressure fluid is respectively passed and exhausted from the upper end of the cylinder K' in response to the adjustment of a valve mechanism L. As shown in Fig. 5, the platen I is formed with an opening or cavity i which may have horizontal dimensions substantially the same as, or slightly larger than those of the transparency E held in the mount having its sections A and B bonded together while the portions of said sections surrounding the transparency are compressed between the platens I and J. The platen J is formed with a similar opening cavity or well j, similar in shape to, and in register with the opening or cavity i. In practice, I have found it advantageous to subject the portions of the mount clamped between the platens I and J to a pressure of a couple hundred pounds per square inch. As previously indicated, the bond between the mount sections A and B may be established by a pressure of a couple of pounds per square inch or so. The use of the pressure of 200 pounds or so per square inch is advantageous because it materially speeds up the bonding operation, largely, I believe, because the greater rapidity with which the adhesive material is heated to a softening temperature, and also because it effects a suitable and suitably rapid elimination of the projections and indentations formed by the embossing action which produces the projections G.

With the bonding pressure applied to the blank between the platens I and J as described, the adhesive material between the sections A and B and the marginal portion of the transparency, does not adhere to the latter. In consequence, the transparency is free to expand and contract in response to changes in its temperature and has no tendency to buckle as a result of such expansion. The term "transparency" as used in the appended claims is intended to designate and include transparent and semi-transparent bodies such as photographic positives and negatives bearing images or designs which may be visually observed when light is transmitted through said bodies.

The procedure hereinbefore described in detail results in the formation of the mount shown in Fig. 3 in which the transparency E is sealed in place and the entire bond between the blank sections A and B is formed in a single press operation. In a modified form of the invention, the mount is formed from a blank which may be exactly like the blank C shown in Fig. 1 except that the projections at one side of the aperture b are preferably omitted. In the preferred form of the invention now to be described, the blank portion from which the projections are omitted is

the portion of the blank at the right of the aperture b as seen in Fig. 1. In such modified form of the invention, the formation of the mount with a transparency sealed therein comprises two bonding operations, in each of which the folded blank sections are subjected to pressure and a portion of the adhesive bond between them is formed.

The effect of the first bonding operation is to establish a bond between portions of the sections above and below, and at the left hand side of the aperture b, as seen in Fig. 1, but does not bond together the portions of the sections at the right hand side of the aperture b as seen in Fig. 1. The first bonding operation may be readily carried out in a press differing from that shown in Fig. 4 only by the replacement of the lower platen I by the platen IA shown in Fig. 6. The platen IA differs from the platen I, in that it includes no portion corresponding to the portion of the platen I at the right of the platen aperture ia. Stated differently, the aperture ia of Fig. 6 is open at its right hand end, and is elongated so that it extends to the right hand end of the platen. Furthermore, the aperture ia is increased in size so that the projections G above and below, and at the left hand side of the aperture ia will be only partially flattened in the initial bonding operation. In consequence, after the initial bonding operation is completed, a transparency may be pushed into the thin space between the portions of the blank sections at the margin of the apertures a and b therein, and at the side of the sections remote from the fold line D, and into engagement with the projections G at the upper and lower sides and left hand end of the aperture b. After a transparency has thus been put into place in the partially finished mount, the latter is subjected to a second bonding operation in which substantially all of the projections G are pressed back into the section B, and in which the previously unbonded portions of the section at the right hand end of the mount and immediately adjacent the top and bottom and left hand edge of the transparency are bonded together.

As will be apparent, the mount in the partially completed form in which it is left at the end of the first bonding operation, constitutes an article of manufacture which may be sold to, and used by amateur photographers and other users. In such case, each mount may be completed by the user after inserting a transparency into the mount so that it extends across the registering apertures a and b and engages the projections G at three sides of the aperture a. In such case, the final bonding operation may well be effected by the use of a hot flat-iron manually pressed against the upper side of the mount, though where desirable, the second bonding operation may be effected by the use of a press of the form collectively shown by Figs. 4 and 5.

While in accordance with the provisions of the statutes, I have illustrated and described the best forms of embodiment of my invention now known to me, it will be apparent to those skilled in the art that changes may be made in the forms of the apparatus disclosed without departing from the spirit of my invention as set forth in the appended claims, and that in some cases certain features of my invention may be used to advantage without a corresponding use of other features.

Having now described my invention, what I

claim as new and desire to secure by Letters Patent is:

1. The method of forming a transparency mount made from a paper blank having a fold line between two side by side sections of said blank, and having an aperture in each section in position to register with the aperture in the other section when the blank is folded on said fold line to bring one side of each section into contact with one side of the other section, which consists in embossing the blank to form projections extending away from said one side of one of said sections and distributed along the outer edge of a portion of the section surrounding the major portion at least of the aperture therein and thereby defining a transparency seat, applying adhesive material to one at least of said sections, placing a transparency on said seat, folding the blank on said fold line to bring said section sides into contact with one another and to bring said apertures into register, and subjecting the folded blank to transverse pressure forcing substantially all of the projections back into the body of the blank section of which they form a part, and establishing an adhesive bond between the contacting sections.

2. A method as specified in claim 1 in which the projections are distributed along the outer edge of a portion of the section surrounding the entire aperture and in which the projections are pressed back into the body of the blank and in which the pressure forcing substantially all of the projections back into the body of the blank section and establishing an adhesive bond between the contacting sections is applied in a single operation.

3. A method as specified in claim 1 in which the projections are distributed along the outer edge of a portion of the section surrounding a portion only of the aperture, except at one side of the latter, and in which the transverse pressure is applied to the mount in a first stage in which the portions of the contacting sections at said one side of the aperture are left unbonded and in which the transparency is moved into engagement with its seat after the completion of the first bonding operation and in which the transparency is sealed in place by a second bonding action uniting portions of the sections at said one side of said seat.

4. A transparency mount comprising a paper blank having integrally connected sections folded into contact with one another and each formed with an aperture in register with the aperture in the other section, one of said sections having been initially embossed to provide projections extending away from the side of that section adjacent the other side of the section and distributed along the margin of a transparency seat on said section surrounding the major portion, at least, of the aperture in the latter, and adhesive material between the contacting sides of said sections, said mount being compressible to establish a thin adhesive bond between the portions of the sections surrounding said major portion at least of said seat, and to substantially force said projections back into the body of the embossed section.

5. A transparency mount comprising a paper blank having integrally connected sections folded into contact with one another and each formed with an aperture in register with the aperture in the other section, one of said sections having been initially embossed to provide projections extending away from the side of that section adjacent the other side of the section and distributed along the margin of a transparency seat on said section surrounding the aperture in the latter, a transparency between said sections comprising a portion in register with said apertures and a rim portion engaging said seat, and adhesive material between the contacting sides of said sections, said mount being compressed to establish a thin adhesive bond between the portions of the sections surrounding said transparency and to substantially force said projection back into the body of the embossed section.
